UNITED STATES PATENT OFFICE.

JAMES H. BULLARD, OF SPRINGFIELD, MASSACHUSETTS.

COMBINED LIQUID RECEPTACLE AND PUMP.

SPECIFICATION forming part of Letters Patent No. 480,068, dated August 2, 1892.

Application filed January 18, 1892. Serial No. 418,370. (No model.)

To all whom it may concern:

Be it known that I, JAMES H. BULLARD, a citizen of the United States, residing at Springfield, in the county of Hampden and State of Massachusetts, have invented new and useful Improvements in a Combined Liquid Receptacle and Pump, of which the following is a specification.

This invention relates generally to improvements in that class of liquid-receptacles which have combined therewith pumping mechanism for expressing or delivering the liquid without the necessity of tipping the receptacle.

15 The invention particularly relates to peculiar constructions or formations whereby increased advantage is realized in the practicability and economy of construction and in the utility and convenience of the apparatus 20 to the user.

To these ends the invention consists in the constructions and combinations of parts, all substantially as will hereinafter fully appear, and be set forth in the claims.

25 The invention, as will be manifest, is of especial utility in tea-kettles or coffee-pots, oil-cans, &c., and in the accompanying drawings the receptacle is illustrated as in the form of a tea-kettle.

30 Figure 1 is a central vertical section of the combined kettle and pump inclosed therein. Fig. 2 is a horizontal section on line 22, Fig. 1. Fig. 3 is a plan view of an upper portion of the kettle adjacent the cover-opening. Fig. 4 is a 35 view similar to Fig. 1, but showing a somewhat modified arrangement of some of the parts; and Fig. 5 is a plan view of the same.

The kettle or receptacle A has the usual entrance-opening for the liquid, and the one 40 here shown has, also, the pouring-spout. B represents an inclosed pump-chamber or sub-receptacle set within the main receptacle, which has at its bottom the valved opening a, the valve being constituted by the ball b, 45 which is seated at the inner orifice of the said opening.

D indicates the piston, which fits and plays in the inclosed chamber, having the rod or stem d, extended upwardly, and at its upper 50 end provided with the handle-knob d'. The said inclosed chamber B has an outlet-open-

ing f, which leads therefrom below the piston and is upwardly extended in the goose-neck pipe g to the outside of the main vessel. The raising of the piston establishes a suction 55 within the lower part of the chamber B, a lifting of the valve and entrance of the liquid into the chamber under the piston, the proper conditions for the suction or vacuum being insured by the provision of the check-valve, 60 (indicated at h in the outlet-pipe.) The downward forcing of the piston insures a pressure upon the liquid thereunder, closing the valve b and forcing the liquid through the outlet past the then opening check-valve for delivery. 65

I regard certain of the details of construction in this apparatus advantageous and important, as well as novel, and will now describe them more in detail.

Referring to the parts constituting the 70 pump-casing, I provide a casting x at the bottom, preferably of malleable iron or brass and of cup shape or annular form, with the bottom closed, except as to the opening a, and having the downwardly-extending supporting-feet z, 75 whereby the said apertured bottom is held slightly above and away from the bottom of the main vessel. The said casting is provided with the lateral hub-opening j for the connection thereat of the outlet-pipe, and has the upper portion of its circular wall formed with an internal socket or rabbet for the reception 80 of the cylindrical shell which constitutes the side walls of the said chamber. The ball-valve is constrained against undue upward 85 movement and for its return to its seat after having been raised, by the cage constituted by the separated circularly-arranged lugs m m, having the inwardly-deflected extremities, the deflection of which may be imparted for 90 the permanent approached relations after the ball has been inclosed. The said lugs are integrally cast as members of said part x. The said bottom casting of the chamber B has the radially-extended spring-arms n n, which at 95 their inner ends are engaged with the casting and which are adapted to have their outer ends in bearing against the lower side walls of the vessel, maintaining the chamber-casing against lateral displacement so far as the 100 lower portion thereof is concerned, while the said chamber-casing has its upper portion re-

strained against sidewise movement by fitting within the internal socket *o*, which is directly of the cover or is of a separable element, which is in engagement with the cover *p*, substantially as shown in Figs. 1 and 4. The flange 5 surrounding the mouth of the vessel may have one or more angular recesses *v*, with which a lug or lugs *w* of the cover *p* may engage.

In the construction and arrangement shown 10 in Fig. 1 the outlet-pipe *g* is extended upwardly through an opening therefor in the cover *p*, and on desiring to remove the cover with it is also lifted all of the parts of the pumping device; but in Fig. 4 the outlet-pipe 15 is shown as extended through the nozzle of the tea-kettle and the chamber-casing fixed against axial movement by the upwardly and outwardly extended spring-arms *q q*, which bear upon the under side of the annular flange 20 which surrounds the mouth or entrance opening of the vessel. In the latter figure the pump-casing has at its upper end a cap *t* of inverted-cup form, which has its upper portion projecting through the opening *u* in the lid, while its outwardly-extended edge flange 25 or lip lies under and in engagement with the portion of the lid bordering its said central opening *u*, said cap being centrally perforated for the play of the piston-spindle. Under 30 this arrangement the lid may be removed for the purpose of refilling the receptacle without disturbing the pumping devices.

Having thus described my invention, what I claim, and desire to secure by Letters Patent, is—

1. In a receptacle and pump of the character described, the combination, with the receptacle, of the contained chamber-casing comprising the casting *x*, of cup form, having 35 the opening *a* in its bottom, the downwardly-extending supporting-feet, the lateral hubbed opening, the upper internal rabbet or socket, and the upwardly-extended lugs *m m*, the ends of which are adapted to be inwardly turned, 40 all integrally formed, and the cylindrical shell *B* fitted in said socket, the piston and its operating-rod, the ball-valve *b* for closing said

opening *a* and restrained against displacement by said lugs *m*, and an outlet-pipe connected to the said lateral opening and extended 50 to the exterior of the receptacle and provided with a check-valve, all substantially as described and shown.

2. In a receptacle and pump of the character described, in combination, a receptacle 55 having an entrance-opening and a closing lid with an aperture therein, a pump-casing contained in the receptacle, having at its lower portion a valved opening leading thereto from the receptacle-chamber and having its upper 60 extremity extended to terminate just below the lid within said aperture and having thereat an inverted-cup-formed cap, which is centrally apertured and having an outwardly-extended flange which lies under the inner edge 65 portion which surrounds the aperture in said lid, the pump-piston with its rod extended through the aperture in said cap above the top of the lid and provided with a handle-knob, and the valved outlet-conduit leading 70 from the pump-chamber below the piston to the exterior of the main receptacle, substantially as described.

3. In a liquid receptacle and pump of the character described, the combination, with 75 the receptacle having an opening within and through its top and a removable centrally-apertured lid for said opening, of the pump-casing centrally set in the receptacle, with the upwardly and outwardly extended spring- 80 arms *q q*, which are adapted to lie under the edge portion of the receptacle-top which surrounds the opening, a valved opening in the bottom of the pump-casing, and the valved outlet-opening and conduit leading from near the 85 bottom of the pump-casing to the exterior of the receptacle, and the piston and rod extended through and above the lid, substantially as and for the purposes set forth.

JAMES II. BULLARD.
